(57) **CLAIM**

The ornamental design for a stylus pen, as shown and described.

DESCRIPTION

FIG. 1 is a front perspective view of a stylus pen showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof;

FIG. 9 is an enlarged view of FIG. 6;

FIG. 10 is an enlarged view of FIG. 7;

FIG. 11 is an enlarged view of the portion 11 encircled in FIG. 1;

FIG. 12 is an enlarged view of the portion 12 encircled in FIG. 1; and,

FIG. 13 is an enlarged view of the portion 13 encircled in FIG. 8.

(Continued)

The dot-dot-dash broken lines in the figures, encircling portions of the claimed design that are illustrated in an enlarged view, form no part of the claimed design.

1 Claim, 13 Drawing Sheets
